UNITED STATES PATENT OFFICE.

RICHARD JOHNSON, OF LIVERPOOL, ENGLAND.

DESIGN FOR A HOLDER FOR SALT, &c.

SPECIFICATION forming part of Design No. 23,980, dated January 29, 1895.

Application filed November 5, 1894. Serial No. 527,981. Term of patent 3½ years.

To all whom it may concern:

Be it known that I, RICHARD JOHNSON, a subject of the Queen of Great Britain, residing at Liverpool, in the county of Lancaster and Kingdom of England, have invented and produced a new and original Design for Holders or Receptacles for Salt, Mustard, or other Like Food Seasonings, of which the following is a specification, reference being had to the accompanying drawing, which shows the holder.

A is the holder, which is oblong in shape and has a raised fence on three sides as shown, and C C are the clipping pieces. These latter are in one piece with the holder, and are formed of three projecting tongues, the mid-

dle tongue being raised above the side ones so as to leave a space nearly equal to the thickness of the rim of a dinner plate. The width of the middle tongue is about equal to both the side tongues put together.

What I claim is—

The design for a holder for salt, &c., substantially as shown and described.

In testimony whereof I have signed my name to this specification in the presence of two subscribing witnesses.

RICHARD JOHNSON.

Witnesses:

G. C. DYMOND,
W. H. BEESTON.
